UNITED STATES PATENT OFFICE.

HENRY NORMAN LEASK, OF LISCARD, ENGLAND.

REFUSE-DESTRUCTOR.

1,149,071.

Specification of Letters Patent.

Patented Aug. 3, 1915.

Application filed November 23, 1912. Serial No. 733,148.

To all whom it may concern:

Be it known that I, HENRY NORMAN LEASK, a subject of the King of England, residing at Liscard, Cheshire, England, have invented certain new and useful Improvements in Refuse-Destructors, of which the following is a specification.

This invention relates to improvements in grates for refuse-destructor furnaces of the 10 type known as trough grate, such as described in my British Patent No. 22,137 of 1909, or of other form.

The object of the invention is to increase the capacity of the grate, to make it easier 15 to break up and cool the clinker of the grate, to enable the fresh charge to restart more easily after the clinker has been withdrawn, and to generally facilitate clinkering of the grate.

20 The invention consists in constructing a trough grate, with one or more hollow projections above the trough bottom upon which the fuel lies and through which air is forced to provide an air supply more 25 nearly to the center of the fire in addition to the lateral supply from the sides, and with a draw bar or draw bars in the bottom of the grate placed below and to project upward through the apex of the hollow pro- 30 jection or otherwise.

The invention will be fully described with reference to the accompanying drawings.

Figure 1 is a transverse section of the improved grate embodying the features of the 35 invention. Fig. 2 is a longitudinal section of the improved grate. Fig. 3 is a transverse section of the grate showing a modification of the clinker draw-bar. Fig. 4 is a top plan view of a portion of the grate embodying the modification as shown by Fig. 3.

The sides A of the trough are preferably made of perforated plates and the bottom B also preferably of perforated solid plates is built up or formed with a central hollow 45 structure C projecting upward toward the center of the trough of such a form that the refuse or fuel can lie at both sides and pile up on top thereof giving to the lower part of the grate the appearance of a double 50 trough.

The upwardly projecting central structure C is of any suitable size and shape preferably having two inclined converging sides meeting at the apex of an angle such sides 55 being somewhat curved or flat in section. Or it may be of semi-hexagonal, octagonal

or cylindrical shape. The top portion of this projection may be made separately so that it may be renewable. The inner sides of this projection may be provided with ribs 60 where desired.

The structure is hollow to form an air passage c throughout the whole length of the trough or only a portion of it or so constructed as to only supply air to one portion 65 of the grate, and is provided with perforations c¹ at the top through the whole or a part of its length and also at the sides to deliver air to the central mass of fuel.

It may be divided internally into compartments as shown in Fig. 2 to each of which the air may be separately delivered.

In the modification shown in Fig. 3 the hollow structure C is provided with a longitudinal slot or slit c² and perforations c¹. 75

The air supply is brought through the side ducts D which provide the lateral air supply to the grate through the apertures d. Or it may be brought through the ash pit or otherwise independently of the lateral air 80 supply, so that it may be used after the lateral supply has been cut off, suitable supply valves or dampers being provided. Or there may be a double set of air supply ducts if desired. 85

It is to be understood that one or two or more of such structures may be fitted on the trough bottom.

The central hollow structure and the grate are preferably inclined downward toward 90 the front of the grate to facilitate the removal of the clinker therefrom.

A draw bar T with or without a draw plate T¹ is placed in the bottom of the grate at each side of the structure C to remove 95 the clinker therefrom and from the bottom of the grate as shown in Fig. 1 (as described in British specification 22137 of 1909).

Or a draw bar T having a draw plate T¹ 100 at one end is placed in the interior of the structure C the end projecting through the longitudinal slit or slot c² in the top thereof as shown in Fig. 3. The draw-bar is notched at intervals to allow of the passage 105 of air directly upward at the apex of the structure C.

This draw bar is so placed that it does not become embedded in the clinker and when a charge of clinker has been withdrawn from the grate by means of it the 110 said draw bar can be returned into position

in the furnace and receive the next charge and thus the one bar is re-used again and again.

In the arrangement shown in Fig. 1 where 5 the clinker rests on the top of the draw bar T there is no difficulty in clearing it of clinker and returning it to the furnace.

Having now particularly described and ascertained the nature of my said invention 10 and in what manner the same is to be performed, I declare that what I claim is:—

1. In a refuse destructor of the class specified, a trough-shaped grate having longitudinal hollow projecting means rising from 15 the grate surface to a level considerably below the upper portions of the grate sides and provided with outlets at the top thereof to bring a supply of air to a point below the surface of the fuel and nearly to the center 20 of the fuel in the grate, the walls of the projecting means being converged in an upward direction, the grate being also provided with a jacket forming a chamber between it and the sides of the grate and projecting nearly to the top of the sides of the 25 grate and to a height above the projecting means, the air space being formed for air which is supplied under pressure to the ash pit and caused to pass upwardly through 30 the said air space over the top edge of the jacket and through the hollow walls of the projecting means to the fire, the air under pressure also reducing the temperature of 35 the edge of the grate to prevent burning out of the same.

2. In a refuse destructor of the class specified, a trough-shaped grate having one or 40 more longitudinal hollow projections rising above the top surface of the grate bottom and provided with outlets at the top thereof to bring a supply of air more nearly to the center of the fire, the walls of the projections being converged in an upward direction, the grate being also provided with 45 a jacket forming a chamber between it and the sides of the grate and projecting nearly to the top of the sides of the grate, an air space being formed for air which is supplied under pressure to the ash pit to pass 50 upwardly through said space over the top edge of the jacket and through the hollow walls to the fire and at the same time reduce the temperature of the edge of the grate to prevent burning out of the same, and one or

more draw-bars having a portion of each in- 55 closed within the one or more hollow projections and provided with a member at an angle thereto and projecting into the fire bed portion of the grate and located at the rear so as to draw the contents of the grate 60 forwardly to the front of the latter.

3. In a refuse destructor, a grate having a trough-shaped bottom with a perforated hollow structure rising therefrom above the said bottom and provided with an air feeding jacket at opposite sides thereof the said jacket feeding air to the hollow structure, and a draw-bar having the greater portion 65 thereof inclosed within the said hollow structure and provided with an angular member at its rear end movable within the trough-shaped bottom close to the said hollow structure to draw the contents of the grate toward the front of the latter.

4. In a refuse destructor of the class specified, a grate having a trough-shaped bottom provided with an apertured hollow structure projecting above the top surface of the bottom and having a longitudinal slot in the upper portion thereof, and a draw-bar 70 mainly inclosed within the said hollow structure and slidably engaging the longitudinal slot, the draw-bar being provided with an angular member at its rear end which is exposed in the trough-shaped bottom 75 of the grate to draw the contents of the latter toward the front of the grate.

5. In a refuse destructor of the class specified, a grate having a trough-shaped bottom with one or more hollow apertured 80 structures projecting above the top surface of the said trough-shaped bottom to deliver air to the center of the body of the fuel, and a draw-bar mounted in each of the structures and mainly inclosed within the latter 85 to prevent embedding of said draw-bar in the clinker, each draw-bar having an angular clinker withdrawing means exposed within the grate, each hollow structure being provided with an air feeding jacket at 90 opposite sides thereof.

In testimony whereof, I have hereunto set my hand in presence of two subscribing witnesses.

HENRY NORMAN LEASK.
